UNITED STATES PATENT OFFICE

161,614

HEAD FOR TOY HOBBYHORSE

Joseph J. Couzens, Oak Park, Ill., assignor to
 Sears, Roebuck and Co., Chicago, Ill., a corporation of New York

Original design application February 15, 1949, Serial No. 866, now Design Patent No. 158,251, dated April 25, 1950. Divided and this application April 21, 1950, Serial No. 9,398

Term of patent 14 years

(Cl. D34—15)

To all whom it may concern:

Be it known that I, Joseph J. Couzens, a citizen of the United States and a resident of Oak Park, in the county of Cook and State of Illinois, have invented a new, original, and ornamental Design for a Head for Toy Hobbyhorse, of which the following is a specification, reference being had to the accompanying drawing, forming a part thereof.

Figs. 1 and 2 are perspective views taken from the front side and rear side, respectively, of a head for toy hobbyhorse embodying my new design.

The side not seen in the drawings is substantially similar to the side shown therein.

This is a division of my application S. N. D. 866 filed February 15, 1949, now matured into Patent No. 158,251.

I claim:

The ornamental design for a head for toy hobbyhorse, as shown and described.

JOSEPH J. COUZENS.
